UNITED STATES PATENT OFFICE.

JOSIAH R. KELLY, JOHN W. KELLY, AND SHELDON A. STIENBARGER, OF AUGUSTA, ILLINOIS.

DENTAL INSTRUMENT.

SPECIFICATION forming part of Letters Patent No. 367,108, dated July 26, 1887.

Application filed October 8, 1886. Serial No. 215,753. (No model.)

To all whom it may concern:

Be it known that we, JOSIAH R. KELLY, JOHN W. KELLY, and SHELDON A. STIENBARGER, citizens of the United States, residing at Augusta, in the county of Hancock and State of Illinois, have invented a new and useful Dental Instrument, of which the following is a specification.

Our invention relates to improvements in dental appliances for extracting teeth without pain; and the object of our invention is to provide a simple means for extracting teeth without exposing the person to the influence of ether or other gases. We attain this object by the mechanism illustrated in the accompanying drawings, in which—

Figure 1 is a side elevation of the entire instrument; Fig. 2, a longitudinal section of a part of the instrument on the line *x x*.

Similar letters refer to similar parts throughout the several views.

Our invention consists in arranging one or more automatic hypodermic syringes in the ends or jaws of pliers, so as to make it easy to thoroughly inject the gums with cocaine or other anaesthetic, and thus prevent all pain in the extraction of teeth. The levers *H H* are like pliers in their general outlines, the jaw parts of which, *C C*, are provided with hollow rubber bulbs *i i*, to which are connected the disks *n n*, into which are inserted the hypodermic needles *f f*. The said syringes thus provided are held in the hollows *I I* in the jaws *C C* by the compressor-springs *s s*, said compressor-springs *s s* being provided with perforations at their outer ends to allow the needles *f f* to pass through them. To the inner sides of the said springs *s s* the rubber dams *D D* are secured, said dams *D D* being also perforated to admit the needles *f f*, and also provided with cavities *e e*, for holding a small quantity of the drug in contact with the gums to deaden the pain which would otherwise be caused by the needles passing through the membrane. Said springs *s s* are also provided with two lighter springs, *m m*, the said springs *m m* being also perforated for the admission of the needles *f f*, the office of said springs *m m* being to keep the points of *f f* from piercing the gums while pressure enough

is applied upon the bulbs *i i* to fill the cavities *e e*, for the purpose above described.

To operate the instrument, one of the springs *s s* is compressed with a finger, while the point of *f f* is kept immersed in the drug to be injected. The pressure being released, the bulb expands and fills itself with the drug, and the jaws *C C* are then inserted into the patient's mouth, so as to clasp the gum near the tooth to be extracted. By gently closing the levers *H H* the dams *D D* are made to conform to the gums, so as to hold a portion of the drug in contact with the membrane, for the purpose hereinbefore described. Increased pressure upon the levers *H H* causes a part of the contents of the bulbs *i i* to be injected into the gums by the springs *m m* yielding and allowing the needles *f f* to penetrate the membrane. The jaws *C C* are provided with longitudinal slots *a a*, which allow the springs *s s* to be compressed through the greater part of their length, said springs *s s* being held in place by rivets *b b*.

We are aware that prior to our invention pliers with absorbing pads attached to their jaws have been used to apply anaesthetics to the gums, and also of the use of ordinary hypodermicsyringes in injecting anaesthetics into the gums.

What we claim as our invention, and wish to secure by Letters Patent, is—

1. The combination, with the jaws of pliers, of one or more automatic hypodermicsyringes, substantially as described, and for the purpose specified.

2. In a dental instrument, the levers *H H*, hinge *j*, jaws *C C*, springs *s s*, secured to said jaws, dams *D D*, secured to said springs, rubber bulbs *i i*, carrying disks *n n*, into which are secured hypodermic needles *f f*, supported by secondary springs *m m*, secured to aforesaid springs *s s*, all combined substantially as described, and for the purpose specified.

JOSIAH R. KELLY.

JOHN W. KELLY.

SHELDON A. STIENBARGER.
